E. WOOD

WATER GAUGE

Filed Oct. 14, 1920

INVENTOR.

Ernest Wood.

UNITED STATES PATENT OFFICE.

ERNEST WOOD, OF YORKTON, SASKATCHEWAN, CANADA

WATER GAUGE.

Application filed October 14, 1920. Serial No. 416,949.

To all whom it may concern:

Be it known that I, ERNEST WOOD, a subject of the Dominion of Canada, residing at Yorkton, in the Province of Saskatchewan, and Dominion of Canada, have invented certain new and useful Improvements in Water Gauges, of which the following is a specification.

My invention relates to improvements in water gauges for steam boilers, or the like, and has particular reference to a water gauge having automatic means to shut off the passage of the steam to the glass tube, when the tube breaks.

An important object of the invention is to provide a device of the above mentioned character, which is simple in construction, and automatic and reliable in operation.

In the accompanying drawings forming a part of this specification, and in which like numerals are employed to designate like parts throughout the same,

Figure 1 is a central longitudinal sectional view through a device embodying the invention, and,

Figure 2 is a plan view of the steam valve.

The numeral 5 designates an upper steam casing, having a flange 7 or web, dividing the same into upper and lower chambers 8 and 9. A laterally extending tube 10 leads into the upper chamber 8, and has a plug or valve body 11, pivoted therein, and adapted to close the same. The tube 10 has a flange 12, which is bolted to the boiler plate 13, as shown at 14.

The upper end of the casing 5 is reduced and screw threaded, as shown at 15, to engage a cap 16, having a longitudinal bore 17, and chamber 18. The bore 17 is closed by a plug 19.

A steam valve is provided, including a tubular body portion 20, slidable in an opening 21, in the flange 7. This tube has its lower end open and its upper end closed, as shown at 22. A disk valve 23 surrounds the tubular body portion 20, extending radially therefrom, at a point beneath and spaced from the closed end 22. This disk valve has apertures 24, and the tubular body portion has apertures 25, which are covered by the wall of the bore 17 when the steam valve is shifted upwardly.

The numeral 26 designates a water casing, provided in its bottom with a drain opening, closed by a plug 27. This water casing has a flange 28, and upper and lower

chambers 29 and 30. The casing 26 is connected with a tube 31, secured to the boiler plate 13 by bolts 32. The numeral 33 designates the upper section of the water casing, having screw-threaded engagement at 34, with the lower section 26. The lower end of the section 33 has a flange 35, provided with an opening 36, this flange forming a chamber 37.

The numeral 38 designates the tubular body portion of a water valve, slidable in the opening 36, and having apertures 39. A disk valve 40 is secured to the lower end of the tubular body portion and projects radially therebeyond, and has apertures 41. The apertures 39 and 41 are covered when the water valve moves upwardly, as is obvious. A valve body 42 is connected with the tube 31.

The numeral 43 designates a glass tube, the upper end of which projects into the lower end of the casing 5, and is held therein by gland nut 44, engaging an iron ring 45, having rubber packing 46 behind it. The lower end of the tube 43 extends into casing section 33 and is engaged by gland nut 47, engaging iron ring 48, in turn engaging a rubber packing 49.

From the foregoing description, it is obvious that should the glass tube 43 break, the steam passing through the opening 10 will quickly shift the steam valve upwardly by engaging the disk 23 thereon, covering apertures 25 by the walls of the bore 17, while the water will shift the water valve upwardly, so that the apertures 39 will be covered by the walls of the bore 36. The steam and water are therefore cut off and prevented from escaping out of the broken tube.

It is to be understood that the form of my invention herewith shown and described is to be taken as a preferred example of the same, and that various changes in the shape, size, and arrangement of parts may be resorted to without departing from the spirit of my invention, or the scope of the subjoined claim.

Having thus described my invention, I claim:

A water gauge adapted for connection to a steam boiler comprising a pair of spaced open ended valve casings, a gauge glass, means for securing said gauge glass to adjacent ends of the valve casings, means forming an upper and lower chamber in

each valve casing including a horizontal member having a passage for establishing communication between said chambers, a valve comprising a disk having a sleeve secured to one face thereof and extending at right angles thereto, said disk having ports adjacent its periphery and said sleeve having ports near its attachment to the disk, means for normally supporting said valves in spaced relation from said horizontal member so that the sleeves thereof are slideable in the passage extending through the member, whereby upon breakage of the gauge glass the valves are caused to move vertically to closed position thereby cutting off communication between the upper and lower chambers in each casing through the ports in the valves.

In testimony whereof, I have affixed my signature in the presence of two witnesses.

ERNEST WOOD.
